UNITED STATES PATENT OFFICE.

BUEL ANDERSON JONES, OF COVINGTON, KENTUCKY, ASSIGNOR TO R. A. JONES & COMPANY, INC., OF COVINGTON, KENTUCKY, A CORPORATION OF KENTUCKY.

CARTON-FEEDING MECHANISM FOR CARTON FOLDING AND FILLING MACHINES.

Application filed January 22, 1925. Serial No. 4,105.

This invention relates to carton folding and filling machines and particularly to the carton feeding mechanism for operating upon a commercial foldable carton in knock-down form, the cartons in the stack or pile being deposited in a magazine with the feeding mechanism conditioning for and ejecting the lowermost carton from the stack and delivering the cartons successively in a progressively timed order.

The cartons in knockdown position in bundles or packs are stacked in the magazine from which the lowermost cartons are successively ejected horizontally from the magazine to be delivered and progressively operated upon for squaring or opening, filling and closing. The withdrawal or ejection of an individual carton from the magazine in the prevailing practice is by means of a reciprocating ejector having a definitely gaged edge engagement with the lowermost carton of the stack, the variation in edge thickness and adherence together of two or more cartons causing frequent choking and interruption in feeding, the shoulder end of the ejector engaging the edge of the carton being of a most appropriate gage to provide a sufficient abutment for pushing the carton and also slide beneath a superposed carton.

With the present invention a portion of the lowermost carton of the stack in the magazine is depressed out of plane with the next adjacent carton to partially separate the same therefrom preferably at an intermediate or central portion thereof, and position such portion of the carton to adapt the ejector to obtain a claw or socket engagement about the edge of the carton and to pass a spacer or separator plate above the carton beneath the supply of cartons in the magazine sustaining their weight to the relief of the lowermost carton and relieving said carton of any frictional withdrawing resistance which would otherwise be encountered.

Therefore, an object of the invention is to provide mechanism for successively feeding or ejecting cartons from a magazine arranged in card-like knock-down form and in a stack or pack deposited in a magazine, adapted to preliminarily depress the lowermost carton to separate the same from the remainder of cartons of the stack, enabling an ejector, having a claw or socket end, to engage about the edge of the carton to ob-

tain a secure hold against the carton for forcibly and efficiently ejecting or withdrawing the carton from the magazine.

Another object of the invention is to depress the lowermost carton by mechanism connecting with the carton by a suction hold, with the suction preferably developed by a moving piston for automatic intermittent action and time control.

Other objects and features of the invention will be more fully set forth in the description of the accompanying drawings forming part of this specification, in which:

Figure 1 is a side elevation of the opposite ends of the carton folding and filling machine showing the improved carton feeding mechanism at one end and the transmission mechanism at the opposite end of the machine, the machine parts intermediate thereof being omitted as they do not form a part of the present invention.

Figure 2 is an enlarged end elevation of the feeding mechanism.

Figure 3 is a section on line 3—3 of Figure 2.

Figure 4 is a section on line 4—4 of Figure 2.

Figure 5 is a section on line 5—5 of Figure 4.

Figure 6 is an enlarged central vertical section through the suction nozzle which connects with the lower side of the lowermost carton in the magazine for depressing a carton.

Figure 7 is a section on line 7—7 of Figure 6.

Figure 8 is a section on line 8—8 of Figure 4.

Figure 9 is a detail side elevation of one of the arms of the carton ejector.

Figure 10 is a detail plan view thereof.

The improvement primarily forms a part of the type of carton folding and filling machine shown and described in Patent No. 1,472,364, dated October 30, 1923, in which the carton feeding mechanism of the present invention may be substituted for the feeding mechanism shown in the patent and as the present invention is only directed to the carton feeding mechanism, parts of an organized machine not forming a part of the feeding mechanism, are omitted, and for which reference may be had to said aforesaid patent.

Referring to the drawings, the machine

2

consists of a pair of end frames 1, 2 suitably connected and upon which a table frame 3 is secured. A pair of journal brackets 4, 5, respectively, are mounted and secured upon the table at its opposite ends providing supports and journals for the longitudinal shafting as a main driving shaft 6 which carries the various cams, not shown, and transmission devices for operating the movable parts of the machine arranged and located above the table. The shaft 6 at one end carries a pulley 7 which is preferably connected to the shaft by clutching devices, not shown. The main driving shaft 6 is provided with a spiral gear 8 in mesh with a spiral gear 9 fixed upon the upper end of a vertical shaft 10, the vertical shaft being suitably supported and journaled at one end in a bearing 11 secured to the bracket 5 and at its opposite end within a bearing 12 secured to the end frame 2. A second spiral gear 13 is fixed to the opposite end of the vertical shaft 10 and in mesh with a spiral gear 14 fixed upon the horizontal shaft 15 which extends longitudinally of the machine frame and beyond the opposite ends thereof below the table. This shaft 15 transmits motion to a cross shaft 16 journaled in bearing brackets 17 fixed to the end frame 2, the shaft 15 having a spiral gear 18 fixed thereon in mesh with a spiral gear 19 upon the shaft 16. The shaft 16 supports a plurality of cams and transmission devices for actuating or reciprocating the various parts of the machine arranged below the table but in the drawings only such transmission elements are shown as are employed for operating the feeding mechanism.

The cartons in a pack are stacked within a magazine located above the table at the receiving end of the machine so that the lowermost cartons of the stack can be successively ejected. The magazine preferably is of skeleton or slat form and comprises a pair of oppositely disposed vertical angle bars 20, 20 secured respectively to lateral arm extensions 21 extending from the table over-hanging portion of the end bracket 4. These angle bars form the end guides for the cartons disposed in the magazine and are spaced apart to conform to the measurements of the cartons. The forward limbs of the angle irons at their upper portion are bent slightly forward or outwardly as shown in Figure 1 to offer freedom in depositing the cartons within the magazine. A plurality of bars 22 fixed to the table overhanging portion of the end bracket 4 form opposite side guides or wall for the magazine. The cartons in the magazine normally rest upon a plurality of base rails consisting of a pair of intermediate base rails 23 each having at one end an angle extension 24 for securing the rail to the lower end of its respective angle bar 20, and 25 indicates

edge rails respectively fixed to the lower end of the angle bars 20 of the magazine and extend forwardly beyond the magazine, as shown in Figure 4, for supporting and guiding the opposite ends of the lowermost 70 carton as it is ejected from the magazine.

The cartons lie in a horizontal plane so that the lowermost carton can be moved in a forward direction beneath the front wall or slats 22 of the magazine by an 75 ejector engaging the rear edge of the folded or flat carton, the ejector being slidably mounted upon a guide block 26 secured upon the table frame 3 beneath the magazine and extending longitudinally beyond the end of the table frame, its upper face having a longitudinal dove-tail groove for receiving a slide plate 27. The slide plate 27 supports and carries a forwardly extending ejector 28 of yoke or prong form. The forward ends of the prongs or tines 29, 29 of the ejector are each enlarged to provide forwardly extending spaced and different length lips 30, 31, to form a socket 90 for receiving the carton and engage about the edge of the carton to obtain a very substantial hold upon the carton and sustain the same against vertical displacement or release from the ejector as the ejector moves forwardly to convey the carton from the magazine. The lower lip 31 is extended to provide an ample support for the carton and the forks or tines are suitably spaced apart for a two-point engagement with the carton and prevent any distorting action 95 upon the carton during its withdrawal movement which would misdirect or improperly track the same upon the guide rails or tracks 24.

The slide plate with its ejector is reciprocated upon the slide block by a lever 32 pivotally connected at one end upon an arm extending from a journal bracket 33 fixed to the end frame 1. The opposite end of the lever 32 is pivotally connected to the link 34 which in turn is pivotally connected to an ear depending from the lower side of the slide plate 27. The lever 32 is actuated by a lever 35 pivotally mounted upon the bracket 17 fixed to the end frame 2 and the levers 32 and 35 are connected by a lever 35a. The lever 35 is provided with a laterally extending pin 36 engaging into a cam groove 37 of the cam wheel fixed upon the cross shaft 16. Thus the ejector is reciprocated upon each revolution of the cam wheel to permit the ejector to obtain a claw-like or socket engagement with the end edge of the carton and also to separate a lowermost carton of the stack or pile within the magazine from its next adjacent carton and insure a positive separation of the carton. The lowermost carton is slightly depressed or bowed intermediately. This also arranges for the spacer blade to be passed be-

tween the cartons, the spacer blade sustaining the weight of the cartons within the magazine and relieving the lowermost carton of such weight or any frictional resistance which they may exert upon the withdrawing carton. The depressing of the carton is accomplished by a reciprocating plunger 38 guidingly supported beneath the magazine within the slide block 26 and table frame 3, its upper end being provided with a nozzle 38^a adapted to bear against the lower side of the lowermost carton and by means of the suction pressure connect with the carton to draw the same downwardly with the downward movement of the plunger. The plunger at its lower end pivotally connects with a link 39, the link in turn pivotally connecting with an arm of the lever 40 pivotally mounted upon a frame connecting tie rod 41 the lever having a laterally extending pin 42 engaged into a cam groove 43 of a cam wheel 44 fixed upon the lower driving shaft 15 extending longitudinally of the machine frame, the cam groove being of a form to reciprocate the plunger for a definite stroke degree and hold the same in its downward or forward stroke limit for a definite timed period while the ejector is being moved forward for withdrawing or ejecting the carton.

The nozzle 38 is represented as an elastic or rubber cork fitting a central opening therethrough through which a flange nipple 45 is engaged for securing the nozzle upon the end of the L-conduit fitting 46 removably secured upon a laterally extending arm 47 fixed to the upper end of the plunger rod 38. The L fitting 46 connects with one end of the tube 48, the opposite end of the tube connecting with a cylinder head 49 of the pump cylinder 50 with which the tube connects. The pump cylinder is mounted upon the frame 3 by a bracket 51. The cylinder is provided with an opening or valve port 52 at the appropriate location to relieve the suction when the piston 53 in its descent opens said port, this being after the plunger has sufficiently depressed the carton and a spacer blade inserted between the lowermost carton and next adjacent carton, so as to avoid the lowermost carton from springing back into its normal position.

The piston 53 is secured to a rod 54 with the lower end of the rod pivotally connected to one arm of the bell crank lever 55 fulcrumed upon a tie rod 56 connecting the end frames. The opposite arm of the bell crank lever 55 pivotally connects with the connecting link 57 connecting with the crank gear 58 fixed upon the shaft 15. The suction stroke of the piston is timed to move slightly in advance of the descent of the plunger 38, so that the nozzle 38^a will obtain a suction hold with the lower side of

the carton before the plunger is retreated and the suction is cut off before the plunger reaches its limit of retreat stroke. Likewise the operation of the ejector is timed so that it will engage the edge of the carton before the suction is cut off to insure a complete socket or claw engagement between the carton and the ejector.

It is obvious other forms of suction generating means may be employed but in utilizing a pump as a part of the feeding mechanism with its piston operated in timed movement with the ejector and other elements of the feeding mechanism provides for a very serviceable, simple and efficient means for accurate timing control, particularly as to starting and duration for high speed results.

While depressing the carton or before the suction pressure thereon has been released, a spacer member or blade 59 is moved between the separated cartons to positively separate the lowermost carton from its next adjacent carton and to sustain the weight of the cartons in the magazine and thereby relieve the lowermost carton of such weight and also to provide a top guide for the lowermost carton as it is being ejected from the magazine. The spacer blade 59 is provided with a tongue end 60 which in the complete forward movement of the blade engages into a notch in the lower edge of the central front wall slat 22 of the magazine, so that the blade reaches the full width of the magazine and extends below the front wall thereof so that the carton is guided for its entire width within the magazine and thereby prevents its forward end from buckling upward when the ejection of the carton commences. The spacer blade 59 is fixed upon a cross plate 61 secured upon a slide 62, the slide being supported upon a rail 63. The rail is fixed to lugs extending from one side of the guide blocks 26 and the slide 62 pivotally connects with a connecting rod 64 and the opposite end of the connecting rod extends to the opposite end of the machine frame and pivotally connects with the lever 65 fulcrumed upon the bracket 17 fixed upon the end frame 2. The lever 65 is provided with a laterally extending pin engaged into a cam groove of a cam wheel fixed upon the shaft 16. With each revolution of the cam wheel the slide 62 is reciprocated at a definitely timed interval coordinate thereto and with the operations of the ejector and carton depressing mechanism.

In the operation of ejecting a carton the plunger is moved upwardly to bring the nozzle in engagement with the lowermost carton in the magazine. The cam actuates the plunger to permit the plunger to have a slight idle interval at its uppermost carton engaging elevation until the pump piston has moved downwardly to develop suf-

- ficient suction for a holding connection of the nozzle with the carton. The plunger 38 is then retracted depressing or bowing the lowermost cartons to separate the same 5 from the next adjacent carton and to bring the carton upon the lips 31 of the ejector. With the depressing of the carton at the proper timed interval the separator blade 39 is moved and inserted between the two 10 lowermost cartons and likewise the pump suction is released after the piston 53 passes beyond the ports 52 which timing is preferably before the plunger 38 reaches its limit of descent and after the ejector has 15 engaged with the carton to insure the socket engagement between the lips 30 and 31 of the ejector, so that when the carton is released by the nozzle it cannot spring out of engagement with the ejector. The nozzle 20 is lowered after release from the carton to provide sufficient clearance for the ejector. The movement of the separator blade is also preferably timed so that it has reached the limit of its forward stroke before any perceptible advance of the carton is made, 25 which guides the carton for the full width of the magazine to prevent any interference to the carton passing beneath the front wall of the magazine.
- 30 The proper timing of the various parts adds materially to the efficient ejecting of the cartons at high speeds. The mechanism is susceptible for feeding flat or card-like products, as folded circulars or other sheets 35 of paper and for the disclosure, reference is generally made to the ejecting of the collapsed flat carton which, however, is not intended to imply any limitation.
- Having described my invention, I claim:
- 40 1. In a device of the class described, a magazine for supporting a stack of cartons, said magazine having a discharge opening at its lower forward end, a slide block providing a slide-way in the nature of a slot 45 beneath said magazine, a slide bar secured to the side of said slide block, a suction nozzle adapted to move vertically and bow the lowermost carton, a separator guided by said slide bar adapted to be horizontally interposed between the withdrawn carton and next adjacent cartons, an ejector operating in said slide-way, yoked about the separator, adapted to move said lowermost carton longitudinally, a suction cylinder adapted to 55 supply the suction for said suction nozzle, and means for operating said members in coordinated relationship.
2. In a device of the class described, a magazine for supporting a stack of cartons, 60 said magazine having a discharge opening at its lower forward end, a slide block having a slide-way therein beneath said magazine, a block adapted to move longitudinally in said slide-way, a yoke-shaped ejector element secured to the top of said block, a 65 slide bar secured to the side of said slide block, a tongue-shaped separator between the arms of said yoke pusher, a slide element on said slide bar joined by a connecting plate to said separator, a suction nozzle vertically operable under the center of said magazine, a suction generating member, and means to coordinate the operation of said elements from a single source of power so that the suction nozzle bows the lowermost 70 carton, the tongue-shaped separator is interposed between that carton and the next adjacent carton, and the ejector comes forward, feeding said bowed and separated carton through the open lower forward end 75 of the magazine.
3. In a device of the class described, a frame on which are mounted a magazine for supporting a stack of cartons, said magazine having a discharge opening at its lower forward end, a slide block beneath said magazine, having a slide-way therein, a block adapted to reciprocate longitudinally in said slide-way, a yoke shaped ejector secured to the top of said block, said ejector having the forward ends of the arms of the yoke provided with lips adapted to engage a carton, a slide bar secured to the side of said slide block, a tongue-shaped separator between the arms of said yoke pusher, a slide element on said slide bar joined by a connecting plate to said separator, a suction nozzle vertically reciprocating under the center of said magazine, a piston and cylinder adapted to create suction connected by a rubber hose to said suction nozzle, and means to coordinate the operation of said elements from a single source of power so that the suction nozzle bows the lowermost carton, 90 the tongue-shaped separator is interposed between that carton and the next adjacent carton and the ejector comes forward feeding said withdrawn and separated carton through the open lower forward end of the magazine.
4. In a machine of the class described, a magazine for supporting a stack of collapsed flat cartons, and a reciprocating ejector for successively ejecting the cartons operating upon the lowermost carton of the stack, 100 said ejector having forwardly extending spaced and different length lips, the lower lip being the longer to support the carton, the upper lip shaped to form in conjunction with the lower lip a socket for receiving the bowed carton and engaging about the edge of the carton to obtain a very substantial hold upon the carton and sustain the same against vertical displacement or release from the ejector as the ejector moves forwardly to convey the carton from the magazine.
- 105 In witness whereof, I hereunto subscribe my name.

RUEL ANDERSON JONES.
